US00D921498S

(12) **United States Design Patent** (10) Patent No.: **US D921,498 S**
Mennicke et al. (45) Date of Patent: ** Jun. 8, 2021

(54) **GROUND PENETRATING RADAR
DETECTION DEVICE**

(71) Applicant: **Proceq AG**, Schwerzenbach (CH)

(72) Inventors: **Ralph Mennicke**, Uster (CH); **Reto Tremp**, Benken (CH); **Roman Schnell**, Basel (CH); **Simon Bürdel**, Aarau (CH); **Marcel Poser**, Oberuzwil (CH); **Patrick Waller**, Dübendorf (CH); **Michael Geiser**, Zürich (CH)

(**) Term: **15 Years**

(21) Appl. No.: **35/508,914**

(22) Filed: **Aug. 12, 2019**

(80) **Hague Agreement Data**

Int. Filing Date: **Aug. 12, 2019**

Int. Reg. No.: **DM/206523**

Int. Reg. Date: **Aug. 12, 2019**

Int. Reg. Pub. Date: **Mar. 27, 2020**

(51) **LOC (13) Cl.** 10-05

(52) **U.S. Cl.**

USPC **D10/47**

(58) **Field of Classification Search**

USPC D10/42, 47

CPC B41J 3/407; F41H 11/12

(57) **CLAIM**

The ornamental design for a ground penetrating radar detection device, as shown and described.

DESCRIPTION

1. Ground penetrating radar detection device

1.1 : Perspective

1.2 : Perspective

1.3 : Front

1.4 : Back

1.5 : Left

1.6 : Right

1.7 : Top

1.8 : Bottom
